UNITED STATES PATENT OFFICE.

CHARLES MARSHALL, OF LEEDS, ENGLAND, ASSIGNOR TO JOSEPH CASH, OF TIPTON,
STAFFORD, ENGLAND.

JAR RAM AND OTHER MOLDING MACHINE.

Application filed February 1, 1923. Serial No. 616,412.

To all whom it may concern:

Be it known that CHARLES MARSHALL, a subject of the King of Great Britain, residing at 32 Woodsley Road, Leeds, in the 5 county of York, England, has invented a new and useful Improvement in or Relating to Jar Ram and Other Molding Machines; and he does hereby declare the following to be a full, clear, and exact description of the 10 same.

This invention relates to jar ram molding machines where sand or other material is rammed in a box or flask around a pattern or into a core box, both of which are used 15 in casting metals.

The object of this invention is to produce a simple and inexpensive portable machine which may be operated by hand for packing the sand or other material around the pattern and for raising the box or "flask" off 20 the pattern.

The invention consists of a jar ram molding machine adapted for reciprocal manual operation by means of a lever or other device, wherein the molding table is resiliently 25 supported by a spring or springs which effect or aid the return movement of the table. The invention also resides in the improved construction and arrangement of 30 parts constituting the machine as will be hereinafter more fully described.

The preferred construction of the present invention will now be described with particular reference to the accompanying sheet 35 of drawings, but the invention is not limited to the details of construction and arrangement shown thereby as considerable departures may be made within the scope of the claims appended to this specification.

40 Fig. 1 is a part sectional side elevation of the molding machine.

Fig. 2 is a plan of the machine.

Fig. 3 illustrates a means for maintaining the molding box or flask in a raised position, and

Fig. 4 is a plan of Fig. 3.

According to the illustrated construction of this invention and referring first more particularly to Figs. 1 and 2, on a bed plate 50 5 is cast a pillar 6 having a flange 7 near its upper end, the pillar 6 is of tubular construction and has its upper portion formed with a cylindrical aperture adapted to receive the cylindrical vertical plunger or ram 8 which carries the table 9. The table 9 is

either cast on or fixed to the upper end of the plunger or ram and the plunger or ram is formed with a central cylindrical aperture 8^a, and a slotted bottom section 8^b. On the outside of the pillar 6 and to the one side 60 thereof are formed two pairs of brackets 10 and 11 the brackets 11 being disposed on either side of a vertical slot 12 formed in the one side of the pillar 6. Through this slot is passed a lever 13 for intermittently 65 lifting the plunger or ram 8. This lever is mounted on a spindle 14 carried by the lower pair of brackets 11 and the outer projecting end of the said lever is pivotally connected by a link 15 bifurcated at each end to the 70 projecting end of a lever 16 fixed upon a spindle 17 mounted in the upper pair of brackets 10. The inner end of the lever 11 is arranged to pass into a slot 8^c in the plunger 8 and to be pivotally connected by means 75 of a link 18 which is bifurcated at the lower end to the plunger or ram 8 the connexion being made by means of the pin 19 fixed in the cylinder or ram 8. Mounted on the spindle 17 is the operating hand lever 20 80 which is curved to the required shape and bifurcated at its outer and free end to receive a transverse bar 21 mounted upon a spindle which forms a handle for operating purposes. The inner end of the lever 20 is 85 cranked inwards as seen in Fig. 2 and the cranked end of the lever is provided with a central hole for loosely mounting the lever upon a flanged boss 22 which is fixed to the spindle 17. The cranked end of the lever 90 is retained in position on the spindle 17 by means of the collar 23.

In the flange of the boss 22 are provided notches 22^a with which the inner end of a sliding circular rod 24 carried by the said 95 lever 20 is adapted to engage, the outer end of the said rod is pivotally connected to a hand lever 25 which is fulcrumed by means of the pin 26 on the lever 20. In its normal position the inner end of the rod is in engagement with one of the notches 22^a in the flanged boss. This rod 24 forms the means of connection for the hand lever 20 with the spindle 17 and determines (according to the notch 22^a in the flanged boss 22 with 105 which it is in engagement) the angular position of the lever 20 to the spindle 17, and also serves to maintain the lever 20 in its lowest position when desired as will be hereinafter described.

To the lever 16 is secured a transverse pin 26^a which projects on both sides of the lever 16 and to this pin are connected two spiral springs 27 which are connected at their lower ends to a treadle lever 28 by means of the transverse pin fixed thereon. This treadle lever is fulcrumed at its inner end by means of the pin 30 to the base of the pillar 6. The treadle lever is arranged to engage any 10 one of a series of notches or teeth 31 formed on a guide bar 32. The guide bar is fixed to the bed plate 5, the said treadle and notches or teeth serving to effect an adjustment or variation of the tension of the 15 springs 27 as required.

The plunger or ram 8 is raised by a vertical spiral spring 33 carried within the pillar 6. The spring is retained in position by projections 34 and 35 respectively attached 20 or formed on the bottom 8^b of the plunger 8 and the upper face of the bed plate 5. When the table is in its lowest position the spring 33 will be compressed and as soon as 25 the operating handle 20 is raised the spring will assist in raising the plunger or ram for jolting or other purposes.

To maintain the hand lever 20 in its position the rod 24 is engaged with the notch in the flanged boss designated 22^a in Fig. 1, 30 to effect this engagement the boss 22 has to be slightly rotated anti-clockwise and thereby through the lever 16 link 15 and lever 13 positions the link 18 on the opposite side of the vertical centre-line passing 35 through the pin 26 to that seen in Fig. 1, and thereby the pressure exerted by the spring 33 tends to hold the lever 20 in its lowest position when released.

For the purpose of maintaining the 40 molding box or flask in a raised position above the table 9 when required a mechanism as illustrated in Figs. 3 and 4 may be employed but this invention is not limited to the particular means illustrated as considerable variations may be made in the 45 construction of this part of the mechanism or it may be dispensed with altogether. The box or flask 36 is carried by means of four vertical arms 37 each formed with a step 50 at the top end to receive the flange of the upper section of the box or flask 36. The arms 37 are secured by means of set screws 38 to brackets 39 pivotally mounted as pairs on the two horizontal rotatable rods 40 55 loosely mounted in brackets 41 secured to extensions of the flange 7 of the pillar 6. Secured to the one end of the pair of rods 40 are cranks 42 and 43 which are pivotally connected to rods 44 and 45 respectively, 60 the rods in turn being pivotally connected to a two-armed lever 46 which is fulcrumed by means of a bolt 47 on the pillar 6. It will be clear that in the event of a rocking action being imparted to the two-armed 65 lever 46 say by means of the flynut 48 that

the four arms 37 are rocked with the pair of spindles 40 and the arms can be caused to occupy the vertical position seen in Fig. 3, or can be moved outwardly so as to free the box or flask 37 and admit of it being supported upon the table 9 in readiness for the jarring or jolting ramming operation.

In some cases the operating lever, shafting and lever connections are dispensed with in small machines, and when this is done 75 the table is pressed down by hand for imparting thereto the required jolting motion, and in order to assist the spring in raising the table it may be slightly lifted by the hand of the operator. The supporting 80 levers and parts connected therewith for holding the box or flask in a raised position during the descent of the table would still be used.

Molding machines constructed as herein 85 described can be easily operated by hand, and after the flask or box has been rammed sufficiently by moving the jarring or jolting lever up and down the hinged supporting 90 arms can be raised as described for lifting the box or flask and holding it in position during the descent of the table and the pattern or model of the article to be cast that has been used. After the pattern has been 95 removed from the box or flask the supports 95 are again lowered to their normal position and the plate or table is then ready for the reception of another flask.

Claims:—

1. A jar ram molding machine comprising 100 in combination a base, a table adapted for vertical reciprocation, pivotal linkage in connexion with said table, a shaft, a hand lever mounted on said shaft and pivotally connected to said linkage for effecting reciprocal motion of the table, a spring connected to said lever and a spring disposed below said table for wholly or substantially offsetting the weight of the said table and any load thereon.

2. A jar ram molding machine comprising 105 in combination a base, a table adapted for vertical reciprocation, pivotal linkage in connexion with said table, a shaft, a hand lever mounted on said shaft and pivotally connected to said linkage for effecting reciprocal motion of the table, a spring connected to said lever, means for varying the tension of said spring, and a spring disposed below said table for wholly or substantially 115 offsetting the weight of said table and any load thereon.

3. A jar ram molding machine comprising 120 in combination a base, a hollow pillar, a table adapted for vertical reciprocation, a stem connected to said table, pivotal linkage connected to said stem, a spring controlled hand lever pivotally mounted on a shaft and pivotally connected to said linkage for effecting motion of the said table, a spring 125

disposed below said table for wholly or substantially offsetting the weight of the said table and any load thereon, and means for determining the angular motion of the said lever.

4. A jar ram molding machine comprising in combination a base, a hollow pillar, a table adapted for vertical reciprocation, a stem connected to said table, pivotal linkage connected to said stem, a hand lever pivotally mounted on a shaft and pivotally connected to said linkage for effecting motion of the said table, a spring connected to said hand lever, a treadle connected to said spring, means for varying the tension of the said spring, and a spring disposed below said table for wholly or substantially offsetting the weight of the said table and any load thereon.

5. A jar ram molding machine comprising 20 in combination a base, a hollow pillar, a table adapted for vertical reciprocation, a stem connected to said table, pivotal linkage connected to said stem, a hand lever pivotally mounted on a shaft and pivotally connected to said linkage for effecting motion 25 of the said table, a spring connected to said hand lever, a treadle connected to said spring, means for varying the tension of the said spring, a spring disposed below said 30 table for wholly or substantially offsetting the weight of the said table and any load thereon, and means for maintaining the molding box in a raised position above the molding table.

In testimony whereof, I have signed my name to this specification.

CHARLES MARSHALL.
